UNITED STATES PATENT OFFICE

2,564,560

HULL STERN

Pierre Carlotti, Paris, France, assignor of one-half
to Société des Ateliers et Chantiers de France,
Paris, France

Application June 4, 1949, Serial No. 97,128
In France September 4, 1948

2 Claims: (Cl. 114—57)

1

This invention relates to the construction of ship hull sterns and is more particularly concerned with ship hull sterns which reduce the power necessary to overcome the resistance to forward movement of the hull.

My copending application, Serial No. 788,560, dated November 18, 1947, also relates to ship hull sterns and has for its object the provision of an improved stern structure. The ship stern comprises an appendage which has various characteristics which have the effect of placing the screw, the screw carrier and the rudder substantially outside the boundary zone surrounding the ship hull. This appendage lies in the symmetry plane of the ship and comprises a leading edge disposed at an angle of 60° to 90° with respect to the tangent plane of the hull which it meets at a point above the plane of the hull bottom. The perpendicular portions of the appendage in relation to the symmetry plane of the ship are of hairpin form with two long branches which are substantially rectangular and vertical and the planes tangent to the appendage at its junction to the hull are substantially perpendicular to the tangent planes of the hull at the same point. The outline of the appendage shows a straight portion situated in an extension of the base of the hull and the rear edge of the appendage is formed by two straight lines defining between them an obtuse angle, the apex of which bisects the shaft of the screw.

In the case of a ship with twin screws, the appendage comprises a thick horizontal wing perpendicular to the lateral faces of the central appendage, having sleeves at its two extremities which form bearings for the propeller shafts. The leading edges of the wing and the sleeves are disposed at a substantial distance from the side of the hull.

It is the object of the present invention to provide an improved hull structure which reduces the power necessary to overcome the resistance to forward movement to an even greater degree than that possible by the structure disclosed in my said copending application.

In accordance with the present invention I provide a ship stern structure comprising an appendage of the type above described in combination with a distributor, and also advantageously with a rectifying rudder, the distributor being formed integrally with the appendage, which is suitably modified in form to provide it with distributing surfaces, or being in the form of a separate appendage combined with the first-mentioned appendage. The said appendage, dis-

2

tributor and rectifier rudder have, in one embodiment of the invention, a form similar to the thick portion of an airplane wing with the free edges tapered or rounded. This is also similar in form to the appendage described in my copending application Serial No. 788,560 but having its rear portion reduced to a helical shape so that its transverse sections instead of having an elongated or flattened ellipsoidal form have, as they approach the extremity of the appendage, a form closely similar in structure to that of the sections taken transversely and successively in a portion of a blade of an airplane screw. The modified form of the appendage is, of course, made in the direction corresponding to the direction of rotation of the screw of the vessel with which it is associated.

The combination of a stern as above described with one or more distributor surfaces and advantageously also with a rectifying rudder has the advantage over known distributors and rectifiers that the whirling field provided by the arrangement of the invention is developed outside the turbulent bounds of the hull and not inside this zone, so that the efficiency of the structure is sufficiently increased.

Other objects and features of the invention will be readily apparent from the following detailed description of an illustrative embodiment of the invention with particular reference to the drawings wherein

Fig. 1 is a side elevational view of the aft portion of a ship embodying features of the invention;

Fig. 2 is a plan view of the structure shown in Fig. 1, and

Fig. 3 is an end elevation of the structure shown in Figs. 1 and 2.

Referring to the drawings, the reference numeral 10 designates generally the hull stern portion of a ship having a longitudinally extending body portion of square cross-section and having a generally flat bottom 11 and vertically extending sides. The hull stern portion 10 extends upwardly, inwardly and aft from the bottom and sides, respectively, of the middle body portion of the ship at an approximately constant rate for a substantial portion of the length of the hull. There is thereby provided a generally uniform convex surface 12 throughout the entire stern. As shown in Figs. 1-3, the hull stern 10 has a vertical fin 13 housing a propeller shaft 14 and affixed to the stern 10 along the curved convex surface 12 and extending forwardly from a point forward of the rear end of the stern to a

point aft of the flat bottom 11. The fin 13 is formed of vertical, semi-lenticular transverse cross-sections throughout its length and the bottom 14 of the fin 13 lies in the generally horizontal plane of the flat bottom portion 11 of the hull 10. The forward end 15 of the fin 13 is formed to provide a generally straight edge which extends upwardly and forwardly from the bottom 14 of the fin and meets the convex surface 12 of the hull at an angle within the range of 60° to 90°. The rear end of the fin is formed to provide two edges each of which is curved transversely and in reverse respective directions. The curves meet at the axis of the propeller shaft 16 and afford curved approach paths of water flow to a propeller 17 mounted on the propeller shaft 16. More particularly, as shown in Figs. 1 to 3, each rear edge of the fin 13 is generally straight in the fore and aft direction and slopes aft to meet along the axis of the propeller shaft 16.

While my invention is thus for purposes of illustration embodied in a single screw ship, it will be obvious that my stern construction may also be embodied in multiple screw vessels, e. g. twin screw vessels. It will also be obvious to those skilled in the art that various changes and modifications may be made in the specific embodiment above-described and illustrated in the accompanying drawings without departing from the scope of my invention as defined in the appended claims, and it is intended, therefore, that all matter contained in the foregoing description and in the drawings shall be interpreted as illustrative only and not as limiting the invention.

What I claim is:

1. In a ship having a longitudinally extending body portion of square cross-section including a generally flat bottom and vertically extending sides, the improvement comprising a hull stern portion extending upwardly, inwardly, and aft from the bottom and sides, respectively, of the middle body portion at an approximately constant rate for a substantial portion of the length of the hull thereby providing a generally uniform convex surface throughout the entire

stern, a vertical fin housing a propeller shaft affixed to the stern along the curved surface and extending forwardly from a point forward of the rear end of the stern to a point aft of the flat bottom, said fin formed of vertical semi-lenticular transverse cross-sections throughout its length and the bottom thereof lying in the generally horizontal plane of the flat bottom portion of the hull, the forward end of said fin formed to provide a generally straight edge, said edge extending upwardly and forwardly from the bottom of the fin and meeting the convex surface at an angle within the range of from 60° to 90°, the rear end of said fin formed to provide two edges, each rear edge being curved transversely and in reverse respective directions and said curves meeting at the axis of the propeller shaft to afford curved approach paths of water flow to a propeller mounted on said shaft.

2. The structure as claimed in claim 1 wherein each rear edge is generally straight in the fore and aft direction, and each said rear edge sloping aft to meet along the axis of the propeller shaft.

PIERRE CARLOTTI.
